UNITED STATES PATENT OFFICE.

FRED ELLIOTT YOUNGS, OF DETROIT, MICHIGAN, ASSIGNOR TO EQUITABLE METER COMPANY, OF PITTSBURG, PENNSYLVANIA, A CORPORATION OF PENNSYLVANIA.

GAS-CONTROLLER.

968,021.

Specification of Letters Patent. Patented Aug. 23, 1910.

Application filed February 20, 1909. Serial No. 479,123.

To all whom it may concern:

Be it known that I, FRED E. YOUNGS, residing at Detroit, in the county of Wayne and State of Michigan, a citizen of the 5 United States, have invented or discovered certain new and useful Improvements in Gas-Controllers, of which improvements the following is a specification.

As heretofore constructed gas regulators 10 will only maintain a sufficiently uniform pressure at the inlet of the meter and at the point of consumption, when the quantity of gas passing is within the normal or rated capacity of the meter and pipes leading 15 therefrom. But if the consumption rises above this normal, requiring a greater flow of gas, the frictional resistance to such flow will correspondingly increase, and the gas will not have the same pressure at the point 20 of consumption, even though the pressure at the meter will be unchanged.

The effective area of the weighted diaphragm as ordinarily used in regulators varies at all points of its stroke being greater 25 when the diaphragm is in its lowest position than in any position where a portion of the diaphragm is prevented from upward movement by reason of its attachment to the case or shell, requiring less pressure to support it. At this point the valves are wide 30 open and the flow of gas is greatest while the pressure delivered is less than when the rate of flow is smaller. Within the normal and usually low rated capacity of the 35 meters, this lessening of the pressure as the volume increases, while undesirable, might be negligible, but when combined with the effect of frictional resistance to the flow of the gas in and from the meter, as above explained, it may result in a serious reduction 40 of the pressure at the point of consumption, before the normal capacity of the meter is reached, and when this rate of flow is exceeded, cause much annoyance and trouble.

45 The invention described herein has for its object a construction in which provision is made for maintaining an approximately uniform pressure at the point of consumption regardless of the rate of flow of the gas.

50 It is a further object of the invention to so connect the meter to the regulator that the frictional resistance through them to the

service lines will not vary except with variations in the rate of flow of the gas.

The invention is hereinafter more fully 55 described and claimed.

In the accompanying drawing forming a part of this specification is shown a sectional elevation of my improved regulator.

In the practice of my invention, the shell 60 1 of the regulator has an arm 2 integral therewith or rigidly connected thereto. This arm is provided with a fitting 3 for connection with the outlet of a meter and the service lines. This regulator and the fitting 3 65 are connected respectively to the inlet and outlet of the meter by means of unions, consisting of the swivel portions 4 and the nuts 5 carried thereby. It is preferred that the swivels one or both should be bent as shown 70 so that by turning them in their seals in the shell, the distance between the center of the nuts 5 may be varied to permit of the regulators being attached to meters varying somewhat in the distance between their inlets 75 and outlets. By thus rigidly connecting the inlet and outlet of the meter, the employment of lead pipes, solder joints, etc., are avoided thereby avoiding variations of resistance to the flow of gas due to the bending 80 of the lead pipes.

The case or shell 1 is formed with an inlet chamber 6, a regulating chamber 7 and a relief chamber 8. In the lower wall of the inlet chamber is formed a port or passage 9 85 for the flow of gas into the regulating chamber, such flow being controlled by a valve 10 of any suitable construction carried by the lever 11. One end of this lever is pivotally connected as at 12, to the case or shell, 90 while the opposite end is pivotally mounted in a slot in the lower end of stem 13 which is connected to the diaphragm 14, extending across the upper end of the regulating chamber 7. The edge of this diaphragm is securely clamped between the case or shell 1 and the flange 15 of the cover 16. A weight 17 is carried by the diaphragm, being attached thereto by a screw 18 passing through a portion of the weight and engaging the 95 stem 13 on the underside of the diaphragm, so that the latter is firmly clamped at its middle portion between the weight and the stem. It will be observed that the arrange- 100

ment of the valve and lever, and the connection of the latter to the diaphragm are such that there will not be any lost motion, and the lever and valve will promptly respond to any movement of the diaphragm.

The diaphragms of regulators are frequently injured in shipment and handling by the back and forward movement of the weight and in order to overcome this a recess 19 is formed in the weight 17 for the reception of a stud or projection 20 of the cover or lid 16. This projection is made enough smaller than the recess that there will be no liability of the two rubbing together in the ordinary operation of the regulator, but the projection will prevent any such movement of the weight as would injure the diaphragm during the shipment or handling of the regulator.

An abutment 21 provided with a recess in its face is secured to the underside of the lever 11 and is adapted to receive and retain one end of a thrust rod 22 which projects into the recess in the abutment, while the opposite end thereof extends into and is loosely retained by a recess in the screw 23 screwing into an opening in the wall of the shell. Around this rod is a compression spring 24 bearing at one end against a collar 25 secured to the rod while the opposite end of the spring bears against a washer 26 loosely mounted on the rod and bearing in turn against the end of the screw 23, as shown. The meeting faces of the washer and screw are preferably curved, so that the washer in all positions of the rod will bear uniformly against the end of the screw. The opening in this screw is made sufficiently large to permit of a considerable lateral movement of the rod as hereinafter described. In the operation of the regulator as the gas flows out along the service lines, the diaphragm will drop down by reason of its weight thereby opening the port 9 and permitting a flow of gas into the regulating chamber, and thence through the meter and service lines. It will be observed that when the valve 10 is closed a line passing through the axis of the rod 22 will be nearly in line with the pivot pin 12, but as the lever moves down the axial line of the rod will move farther and farther away from the pivot 12, thus increasing the leverage proportionately to its change in position which corresponds to changes of position of the diaphragm and consequent resultant effect of the force of the spring exerted through the thrust rod to pull down on the diaphragm. Before the regulator is used the several parts are so adjusted that when the effective area of the diaphragm is increased due to its downward movement by the weight, the effectiveness of the spring will increase at the desired rate. The operation of the spring 24 is equivalent to adding an automatically

variable weight to the diaphragm, which becomes greater or less according as the diaphragm is moved downward or upward.

The gases for the regulation of which my improved regulator will be employed, have an injurious effect upon the diaphragm causing a rapid deterioration of the same, and in order to overcome this a removable partition 27 is arranged across the regulating chamber, so as to prevent a circulation of gas in contact with the diaphragm. The opening through the diaphragm for the stem 13 is sufficiently large to permit of free movement of the latter and also to allow the dead gases inclosed between the partition 27 and the diaphragm to freely respond to any variation of pressure in the portion of the regulating chamber below the diaphragm. The regulating chamber is connected to the relief chamber 8 by a short tube 28, which extends down into a recessed plug 29 screwing into an opening in the relief chamber. The lower end of this tube is immersed in mercury, the depth of which above the end of the tube will be regulated in accordance with the maximum pressure which it is desired to maintain in the regulating chamber. In case of an abnormal increase of pressure the mercury will be displaced and allow the gas to escape through the lower end of the tube into the chamber, and pass through the escape port 30 formed in part in the case or shell 1 and partially in an extension of the lid 16. When the seal formed by the mercury is broken the rush of gas is quick and violent, and will force the mercury into the chamber 8 in the form of spray or small drops. In order to prevent this spray being carried out through the escape port 30, baffle walls 31 and 32 are provided, which will deflect the sprayed mercury downward onto the bottom of chamber 8 and thus prevent it being carried out through the escape port. In order that the diaphragm and weight may move freely up and down, a vent port 34 is provided connecting the chamber formed by the diaphragm and cover with the escape port 30. Should the gas be shut off entirely at the inlet of the meter and regulator in cold weather, there will be a condensation of the gases remaining therein, and if the service pipes are tightly closed a greater or less vacuum formed in the regulating chamber. As this vacuum is formed the atmospheric pressure in the relief chamber 8 may force the mercury up into the tube until its lower end is uncovered, when the air would rush through the tube into the regulating chamber. In this rush of air mercury is liable to be displaced and carried violently into the regulating chamber, whence it might pass into the meter and injure the latter by amalgamating with the solder of its shell. To prevent such a sudden rush as would be incident to the uncover-

- ing of the entire end of the pipe 28, a notch is formed in the lower end of the pipe which, when uncovered, will allow a gradual flow of air from the relief chamber into the regulating chamber. 5 the spring being arranged to present a resistance to the closing of the valve approximately proportional to the variations in the effective area of the surface of the diaphragm subjected to gas pressure. 50
- I claim herein as my invention:
1. An integrally formed gas controller casting having arranged therein suitable means for automatically regulating the flow of gas 10 to a meter in combination with threaded means exterior of but integral with the casting for attaching the casing to a gas supply line, to the inlet of the meter, to the outlet of the meter and to service lines.
  - 15 2. A gas controller having in combination a valve controlling the flow of gas from the supply pipe, a uniformly weighted diaphragm subject to gas pressure on one side for shifting the valve, and means operative 20 on an increased flow through the service lines to supplement the action of the weight on said diaphragm proportional to increased resistance in the service lines.
  - 25 3. A gas controller having in combination a valve controlling the flow of gas from the supply pipe, a diaphragm movable by the pressure of the gas for closing said valve, and a spring acting in opposition to valve closing movement of the diaphragm, the spring 30 being arranged to present a resistance to the closing of the valve approximately proportional to the increase in the effective area of the surface of the diaphragm subjected to gas pressure.
  - 35 4. A gas controller provided with regulating and relief chambers, the relief chamber having a free outlet in combination with a basin or receptacle for a sealing liquid, a connection from the regulating chamber extending into said basin and a port permitting a gradual flow of air from the relief chamber to the regulating chamber. 75
  - 40 5. A gas controller having in combination a valve controlling the flow of gas from the supply pipe, a weighted diaphragm movable by pressure of the gas for closing said valve, and a spring acting in opposition to the valve closing movement of the diaphragm, 45
6. A gas controller having in combination a case or shell having inlet and outlet ports, a valve controlling the flow of gas, a diaphragm movable by pressure of gas for closing such valve, and a removable partition so arranged in the case or shell in relation to the diaphragm and the line of flow of gas through the regulator from the inlet to the outlet port, as to prevent material circulation of gas in contact with the diaphragm and without interfering with variations of pressure of the gas flowing through the case or shell, affecting the diaphragm. 60
7. A gas controller provided with regulating and relief chambers, the relief chamber having a free outlet in combination with a basin or receptacle for a sealing liquid, a connection from the regulating chamber extending into said basin and a port permitting a gradual flow of air from the relief chamber to the regulating chamber. 70
8. A gas controller provided with regulating and relief chambers, the relief chamber having a free outlet to the atmosphere, a connection between said chambers, a mercury seal closing one end of such connection, and baffle walls extending in opposite directions into the line of flow of gas to the free outlet to prevent the escape of mercury therethrough. 80
9. A gas controller provided with regulating and relief chambers, the relief chamber having a free outlet to the atmosphere, a connection between the regulating and relief chambers, a mercury seal controlling such connection and a baffle wall extending into the line of flow of gas to the free outlet to prevent the escape of mercury therethrough. 85

In testimony whereof, I have hereunto set my hand.

FRED ELLIOTT YOUNGS.
